US0D1048661S

(12) United States Design Patent (10) Patent No.: US D1,048,661 S
(45) Date of Patent:  Oct. 29, 2024

(54) SHOE

(71) Applicant: BALENCIAGA, Paris (FR)

(72) Inventor: Demna Gvasalia, Paris (FR)

() Term: 15 Years

(21) Appl. No.: 35/518,944

(22) Filed: Oct. 20, 2023

(80) Hague Agreement Data

Int. Filing Date: Oct. 20, 2023

Int. Reg. No.: DM/232752

Int. Reg. Date: Oct. 20, 2023

Int. Reg. Pub. Date: Nov. 10, 2023

(30) Foreign Application Priority Data

Apr. 21, 2023 (EM) 015019072-0002

(51) LOC (14) Cl. 02-04
